FREDRICK BRUENINGSEN AND EDWARD QUINN, OF HASTINGS, NEBRASKA.

FIRE-ESCAPE.

SPECIFICATION forming part of Letters Patent No. 334,741, dated January 26, 1886.

Application filed November 5, 1885. Serial No. 181,899. (No model.)

To all whom it may concern:

Be it known that we, FREDRICK BRUENINGSEN and EDWARD QUINN, citizens of Nebraska, residing at Hastings, in the county 5 of Adams and State of Nebraska, have invented certain new and useful Improvements in the Hastings New Fire - Escape; and we do hereby declare the following to be a full, clear, and exact description of the invention, such as will enable others skilled in the art to which it appertains to make and use the same.

Our invention relates to an improvement in fire-escapes; and it consists in certain arrangements and details of construction hereinafter more specifically described, and pointed out in the accompanying drawings, in which—

Figure 1 represents a side elevation of my 20 device; Fig. 2, a perspective view of the basket or car with its attachments; Fig. 3, a vertical section of the basket. Fig. 4 is a horizontal section through the line x x of Fig. 1.

We employ in constructing our fire-escape a mast, A, of suitable length, size, and material, tapering slightly toward the top, to which the car or basket is secured by rings B B', surrounding and inclosing the mast, and to 30 which the basket is secured in the manner hereinafter described. The rings B B' are of a diameter slightly greater than that of the mast at its largest point, to enable them to slide freely along it, and secured to their inner faces at right angles are two or more short metallic springs, C, in the outer or projecting ends of which are mounted friction-rollers d, designed to bear against the outer face or surface of the mast when the rings 35 close it. To the lowermost ring, B', the rim of the basket or car is securely bolted, and a connecting-brace, E, is also secured thereto, and extends upward for a suitable distance, and is then bolted to ring B, and bent outward and bifurcated, and its branches E' E' 40 carried down to the opposite sides or corners of the basket or car and secured thereto, as shown in Fig. 2. The foot of the mast is provided with a pin or sharp point, i, de-

signed to sink in the ground and prevent the 50 mast from slipping when in position. Upon the opposite or top end of the mast is a triangular or three-pointed plate, F, the corners or points of which are perforated to enable guy-ropes to be fitted and secured there- 55 to. Near the top of the mast is a slot or opening, in which is fitted a pulley, O, and near the foot of the mast is mortised or otherwise secured a short bracket or stud, G, projecting at right angles from the mast, and 60 also fitted at its outer end with a pulley, O'. Over and around these pulleys passes a rope, D, one end of which is secured to the frame or handle of the basket, for the purpose of raising or lowering it along the mast when in po- 65 sition.

When it is desired to operate our device, it is placed in position near the building, as shown in Fig. 1, and firmly secured in place by means of the guy-ropes P, attached to the 70 plate F at the top, and their opposite ends at or near the ground. The power is then applied to the lower end of rope D and the car or basket raised to any window or other opening along the front of the house that it 75 is desired to reach, and when loaded is allowed to descend smoothly and safely to the ground by releasing the tension upon the pulley-rope D, the springs e and friction-rollers d serving to prevent any binding or jar in the 80 descent.

We do not limit our invention to any particular form of basket or car, but prefer a metallic basket of the form shown as the safest and most convenient. The mast may also be 85 constructed of wood, iron, or any other suitable material, and of any convenient size or length.

Having thus described our invention, what we claim, and desire to secure by Letters Pat- 90 ent, is—

1. In a fire-escape, the combination, with a mast, of the inclosing-rings fitted with the interior projecting springs, having friction-rollers in their outer ends, and the basket secured thereto, with means for raising and lowering same, substantially as and for the purpose set forth.

2. In a fire-escape, the combination of the mast A, provided with the plate F, guy-
ropes P, pin i, and pulleys O O', with the
rings B B', having the interior springs, c, car-
rying friction-rollers d, and firmly united to
the basket or car by the brace E E' E², con-
structed substantially as and for the purpose
described.

In testimony whereof we affix our signatures
in presence of two witnesses.

FRED. BRUENINGSEN.
EDWARD QUINN.
